UNITED STATES PATENT OFFICE.

TULLY DE STEFANI, OF CHICAGO, ILLINOIS, ASSIGNOR TO LIQUID CARBONIC CO., OF CHICAGO, ILLINOIS, A CORPORATION OF ILLINOIS.

DRAFT ARM FOR SODA FOUNTAINS.

Application filed March 29, 1926. Serial No. 98,283.

My invention relates to improvements in draft arms for soda fountains, and it consists in the combinations, constructions, and arrangements herein described and claimed.

5 An object of my invention is to provide a draft arm for a soda fountain in which any liquid retained in the draft arm, which has previously been drawn from a cold supply, will remain cold while in the draft arm, so 10 that when the next drink is to be served, the liquid in the draft arm will emerge in a cool state.

A further object of the invention is to provide a draft arm having a block tin tube 15 through which the liquid passes, with a metal casing surrounding this tube and spaced therefrom, so as to give the appearance of a solid arm, means being provided to fill the intervening space with heat insulating material.

20 A further object of the invention is to provide a draft arm of artistic appearance and having a look of solidity, but which is made of sheet metal, whereby the cost is cut down, 25 without, however, sacrificing the appearance or utility.

Other objects and advantages will appear in the following specification, and the novel features of the invention will be particularly 30 pointed out in the appended claim.

My invention is illustrated in the accompanying drawings, forming part of this application, in which

35 Figure 1 is a central sectional view through the draft arm, the discharge head being shown in elevation, and

Figure 2 is an enlarged section along the line 2—2 of Figure 1.

40 In carrying out my invention, I make use of a base portion 1 which is preferably a casting of circular contour. It is provided with an annular flange 2 on the upper side having an annular groove 3 concentric with the central axis of the casting. The bottom portion of the casting has a recess 4. The central portion of the casting consists of a stem 5 which is threaded at 6, and which has a central bore arranged to receive the end of a block tin tube 7.

45 At the upper end of the draft arm, is a member 8 also having an annular recess 9 on one side and a threaded reduced portion 10 on the opposite side, the latter being arranged to receive the threaded connection 11 of a discharge head 12. The block tin

tube, as will be seen, extends centrally of the device and is bent laterally and enters a bore in the member 7.

The outer portion of the draft arm consists of stamped sheet metal. In Figure 2, 50 it will be seen that there are two stampings 13 and 14, respectively, which are joined together to form the outer portion of the arm. These stampings have offset angular portions, such as those shown at 13^a and 14^a, at 55 the corners of the rectangle, formed when the pieces are put together. There are similar offset portions 14^b and 13^b provided at adjacent corners of the rectangle. When these sheet metal stampings are placed together, as shown in Figure 2, it will be observed that the portions 14^b of one of them overlap the portions 13^b of the other. These overlapped portions are soldered together so that the casing has the appearance of a 60 rectangular form with flattened corners. It will further be noted that the device tapers from the bottom to the top.

In Figure 1, the section is taken through the overlapping portions 14^b and 13^b. The 65 bottom edge of the casing thus formed is disposed in the annular groove 2 at the bottom, while the upper edge is disposed in the annular groove or recess 9, being preferably soldered therein so as to make 70 a rigid construction. After the casing has been affixed to the bottom and top portions, the exterior is preferably plated to give it a finished appearance.

75 It will be observed that there is an opening 90 in the base 1. This opening is for the purpose of introducing heat-insulating material 17 into the space between the casing and the block tin tube 7. The material which I preferably use is ground cork. 95 When the interior of the arm has been filled, the hole is closed by a plug 16.

80 From the foregoing description of the various parts of the device, the operation thereof may be readily understood. The base is designed to rest on the top of a counter or table, not shown, and the tube 6 is designed to be connected with a suitable source of supply of cooled liquid. The control of this liquid is effected by the lever 100 or handle 18 of the discharge head 12. The liquid rises through the block tin tube, but does not come in contact with the other metals which might contaminate it, and when the handle is turned, the liquid is 105

forced out of the nozzle 19. When the handle is turned to shut off the flow, there will be liquid in the draft arm, but this will be kept cool by the heat-insulating substance, so that when the next drink is served, the first flow of liquid will be in a cool condition. The fact that the exterior portion of the arm is made of sheet metal makes it light in comparison with solid castings, and also cuts down the expense of making the arm, without decreasing its utility, or sacrificing appearance, which is that of a solid piece.

I claim:

15 In a draft arm for soda fountains, a base member, a top portion, a liquid-conveying tube extending through said base member and said top portion, a sheet metal casing comprising a pair of stamped out portions

provided with longitudinally extending outwardly projecting flat reinforcing portions positioned adjacent the centers and extending the full length thereof, one of said stamped out portions being provided with longitudinally extending outwardly projecting flat reinforcing portions positioned at the connecting edges and extending the full length thereof for receiving the longitudinal edges of the other stamped out portion, the ends of said sheet metal portions being secured to said base member and to said top portion, respectively, said base member being provided with an opening, a heat insulating material passed through said opening and disposed between said casing and said tube, and a plug for said opening.

TULLY DE STEFANI.
